United States Patent Office

Des. 192,698
Patented May 1, 1962

192,698

NEEDLE GAGE

Charles Curello, East Haven, Conn., assignor to Mite Corporation, New Haven, Conn., a corporation of Delaware

Filed July 21, 1961, Ser. No. 66,005

Term of patent 14 years

(Cl. D52—6)

Fig. 1.

Fig. 2.

FIG. 1 is a top plan view of a needle gage embodying my new design; and

FIG. 2 is an elevational view of the gage as viewed from the bottom of FIG. 1.

The bottom of the gage is plain in appearance.

I claim:

The ornamental design for a needle gage, substantially as shown and described.
